PETER RODIER, OF DETROIT, MICHIGAN.

Letters Patent No. 83,411, dated October 27, 1868.

IMPROVEMENT IN STOP-DEVICE.

The Schedule referred to in these Letters Patent and making part of the same.

To all whom it may concern:

Be it known that I, PETER RODIER, of Detroit, in the county of Wayne, and State of Michigan, have invented an Improved Stop-Device; and I do hereby declare that the following is a full, clear, and exact description thereof, reference being had to the accompanying drawings, making part of this specification, and to the letters of reference marked thereon, in which—

Figure 1 is a plan view of my invention;

Figure 2 is a bottom view of the same;

Figure 3 is a view of the friction-bars;

Figure 4 is a side view of the device, with the side cover removed; and

Figure 5 is a side view of the cover.

My invention relates to a device to be used in connection with the belt of any machine, for the purpose of preventing the belt from moving in the wrong direction, and consists of a case or box, in which is placed a bar, or two of them, connected by an arm, against which the belt impinges, when it moves in one direction; in such manner that the bar is brought down more forcibly against the belt, compressing and holding the belt between said bar and the side of the box, or some rigid body placed behind the belt, and thus preventing the belt from moving in that direction, while the said belt is perfectly free to move in the opposite direction, as the friction-bar above mentioned is carried upward and out of constant or firm contact with the belt, by its movement in such opposite direction.

That others skilled in the art may be able to make and use my invention, I will proceed to describe its construction and mode of operation.

I make a suitable metallic case, E, having the sides K N L, as shown in fig. 4, and having also a base, A, with ears B B, having holes a a therein, by means of which to secure it to the table or place where it is to be used. One end of said case is made solid, or in the same piece with the case, while the other is made so that it can be removed from the case E, by making one of the ears B in two parts, or casting the part A' separately from the part B, and upon the part F, as shown in fig. 5, and the edges i i of the base, A', are grooved, and made to fit the sides i i of the base, B. By this construction, the base, A', when inserted between the sides i i, and forced inward to the case E, forms a part of the ear B, while the cover F forms one end of the case E.

A curved recess is made at H, in the case E, and also at I, a rectangular opening being made in the lower side, L, and also a similar opening, O, in the base, A. The sides s s of these openings may be curved or rounded, to facilitate the passage of the belt through said openings. The friction-bar c may be cylindrical in form, and may have upon each end the flange h, to prevent the friction-bands e e from being forced off the bar c by any means. The bar c is connected to the pivot-bar d, which may be also cylindrical in form, by means of the arm b, and upon both the bars c and d are placed

the rubber bands e e and f f. These bars c, d, and b, I denominate a lever, M.

Having thus described its construction, I will now proceed to describe the mode of its operation, which is illustrated in fig. 4, in which P represents, in red lines, a portion of a sewing-machine table, with a belt, Q, passing through it. The cover F of the case E is first removed, and the lever M is inserted within said case E, the bar d of the lever M resting in the curved recess H, the other bar, c, being upward and near the curved recess I. The case E is then placed over or upon the belt, said belt passing into the openings O and O, and the lever M, in the position shown in black lines, in fig. 4. The base, A', of the cover F is then inserted in place between the curved sides i i, and forced up to the case E firmly, and the device is then secured in place to the lower side of the table P, by means of screws inserted through the holes a a. If, now, the belt moves in an upward direction, the lever M is kept in its position, as shown in black lines, in fig. 4, but, if the belt be moved in an opposite direction, or downwards, the friction of the belt against the bar c, or collar thereupon, carries the upper end of the lever M down with it, until the belt becomes wedged in between the upper end of said lever M and the friction-base N, and the belt is thus prevented from moving any farther in that direction, and the machine cannot be operated unless the belt moves upward, or in the right direction.

It is evident that the case E may be made partially open, instead of wholly enclosed, provided the bearing H, and openings C and O, are made so that the lever M shall be retained in place, and press the belt against the friction-base N; and it is also evident that the lever M may be made solid its whole width, and may have one continuous band of rubber or friction-material passing over both ends, and, in practice, it might be found that no rubber or friction-material would be required, as the friction between the belt and the upper part of the lever itself might be sufficient to operate the said lever M, and it might be found unnecessary to have the flanges h h upon the bar c.

The pivot-bar d, or the lower end of the lever M, instead of resting within or against the curved recess H, may have a pin, pivot, or trunnion at each end, resting in proper bearings, made for that purpose, in the ends of the case or frame, but this would be merely an equivalent to my device, as I have used it in that way, but prefer the construction shown.

The friction-bar c and pivot-bar d, at the top and bottom of the lever M, may be octagonal, or any other suitable form, and may have any other friction-material placed thereon, instead of the rubber bands above mentioned, the main object of such material being, in this connection, to form a cushion, and deaden the noise.

This device is adapted for use upon very many machines which are driven by a belt, such machines being designed to operate by driving the belt in one direction, as in most of the sewing-machines now in use, or upon

card-setting machines, and many others, and it is particularly adapted for use upon machines which are driven by hand or foot-power; and, if it should be desired to attach this device to machines in other positions than that shown, it may be done, by placing the base, A, upon any other side of the case E, merely modifying the form of said case to suit the machine to which it is to be attached, and it is equally applicable for use in connection with a round belt as with a flat one, by merely varying the size of the device, and instead of having the friction-base N upon the case, or making a part of the case, that side of said case may be made open, and a block, or piece of timber, or any rigid body may be placed quite near the belt, upon the back side, so that when the upper end of the lever M should be brought down against the belt, it could press the belt against such timber or rigid body, such body thus forming a friction-base, against which the lever and bolt should

operate. It might be found better, in some of the larger and more powerful machines, to form a friction-base, for the lever M to operate against in this way.

Having thus described my invention,

What I claim as new, and desire to secure by Letters Patent, is—

A lever, resting in suitable bearings, and operating automatically, both to stop a belt, by compressing it between the end of said lever and another rigid body, upon the opposite side of the belt, and also to release its hold upon the belt, both operations being performed by the action or movement of said belt itself, substantially as herein described and set forth.

PETER RODIER.
